COMBINED MENU SIGN AND COMMUNICATIONS UNIT FOR A DRIVE-IN RESTAURANT

Henry Dreyfuss, New York, N.Y., assignor to American
Machine & Foundry Company, a corporation of New
Jersey

Filed May 6, 1966, Ser. No. 2,196

Term of patent 14 years

(Cl. D1—12)

FIG. 1

FIG. 2

FIG. 1 is a perspective frontal view for a combined menu sign and communications unit for a drive-in restaurant, showing my new design;

FIG. 2 is another perspective view taken from the top and one end thereof.

The dominant features of my invention reside in the portion shown in full lines, the fragmentary broken line representation of a support pole is for purposes of illustration only.

I claim:

The ornamental design for a combined menu sign and communications unit for a drive-in restaurant, as shown and described.
